UNITED STATES PATENT OFFICE.

JEAN W. BICKS, OF EVANSTON, ILLINOIS, ASSIGNOR TO SPENCER PERFUME COMPANY,
OF SOUTH BEND, INDIANA, A CORPORATION OF INDIANA.

DESIGN FOR A BOTTLE OR SIMILAR CONTAINER.

Application filed June 16, 1928. Serial No. 27,162. Term of patent 3½ years.

To all whom it may concern:

Be it known that I, JEAN W. BICKS, a citizen of the United States, residing at Evanston, county of Cook, and State of Illinois, have invented a new, original, and ornamental Design for Bottles or Similar Containers, of which the following is a specification, reference being had to the accompanying drawing, forming a part thereof.

I claim:

The ornamental design for a bottle or similar container, as shown.

JEAN W. BICKS.
